UNITED STATES PATENT OFFICE.

BIRGER LJUNGSTRÖM, OF STOCKHOLM, SWEDEN.

RADIAL TURBINE.

No. 908,685.

Specification of Letters Patent.

Patented Jan. 5, 1909.

Application filed April 4, 1907. Serial No. 366,344.

To all whom it may concern:

Be it known that I, BIRGER LJUNGSTRÖM, a subject of the King of Sweden, residing at 8 Flemminggaten, Stockholm, Sweden, have 5 invented certain new and useful Improvements in Radial-Flow Turbines, of which the following is a specification.

This invention has for its object to provide means for balancing the axial thrust upon 10 the rotor of a turbine when under the action of the pressure medium.

In order to carry out the purposes of this invention a baffling device of special construction has been made use of which by being positioned upon those faces of the vane supporting disks opposite to the faces upon which the vanes themselves are secured, brings about a compensation in the pressures whereby the pressure upon one side of said 20 rotating vane-supporting disk is automatically regulated to balance that on the other side of the same. In furtherance of this object, it is of importance that the arrangement of the baffling device should be self-regulating so as to meet the requirements placed 25 upon it when working under either constant steam pressure or under sudden alterations in the same, such as occurs when the admission of steam to the vanes is brought about 30 in greater or less degree. To attain these results the baffling means are arranged in suitable casings in direct communication with the ring-shaped interspaces between the vane-supporting disks.

In the accompanying drawings, Figure 1 is a sectional view of a radial flow turbine showing one embodiment of my invention; Fig. 2 is a view also in section showing another embodiment of my invention; Fig. 3 is 40 a view in section of an embodiment of my invention in which there are two oppositely rotating shafts each provided with pressure-balancing vanes; Fig. 4 is a view in section of still another embodiment; and Fig. 5 is a 45 view in section of another embodiment in which the baffling device is shown incased in an elongated portion of the casing.

Referring now to the accompanying drawings in which like characters refer to the same 50 parts wherever used, in Fig. 1, is shown the turbine casing *b* carrying upon the interior wall thereof, a series of fixed vanes *a* while upon the rotor shaft *d* is secured a disk *e* upon which are mounted a series of rotating vanes 55 *c*. Upon the back of said disk *e* are mounted a series of baffling rings *f* which in conjunc-

tion with a series of similar rings secured to the back wall of casing *b* afford a ready means of balancing the axial thrust from the flow of steam through blades or vanes *a* and *c*. 60

Piercing the disk *e* are a number of regularly interspersed holes or channels *g* which serve for the passage of the pressure medium from the blade-containing chamber to the labyrinth rings in the rear whereby the compensation in pressures is effected by the inter-disposition of said rings. These rings are mounted in such manner as to cause the outer edge of each ring to project over into the space between the two adjacent and opposite rings thereby adapting the labyrinth to permit a slow passage of steam therethrough. To insure a minimum loss of steam the labyrinth rings are mounted to have the smallest degree of play consistent 75 with smooth running.

In Fig. 2 will be seen a modification of the device described above, while constructed on the same general principle, it will be noticed that the baffling device has been placed between the back wall of the turbine and a plate *h* connected to the plate carrying the vanes *c*. In this embodiment communication between the blade-containing and labyrinth chambers is effected by means of a plurality 85 of tubes or pipes *i*.

Referring now to Fig. 3 there is shown a pair of conical blade-supporting plates *j* and *k* carrying two series of blades *a'* and *c'* which are made longer as their distance from the 90 rotor-shafts *l* and *m* increases. Since in this embodiment both shafts are rotating, it becomes necessary to have a series of baffling rings for each rotor having the same general arrangement and connections as described 95 above with the exception that in this case the casing of the turbine is better adapted to be cast in halves with a parting plane through the axis of the shaft. This is facilitated by the method of setting up employed which consists in first introducing the rings into the casing loosely and afterwards tightening the same therein.

Referring now to Fig. 4, the vane-supporting disks will be seen to be made up of a number of concentric annular flat surfaces offset one from the other outwardly as they near the periphery of the rotor. The blade-supporting plates as well as the walls of the casing, are by this construction formed with a 105 step-like coned surface which while affording the greater strength in a direction along the

axis, at the same time makes it possible to maintain a uniform radial arrangement of the baffling rings. In the arrangement of the thrust counterbalancing device upon the outer surfaces of the vane-supporting plates, a pressure is maintained upon said plates in such a direction as to hold them together against the pressure tending to spread them apart.

- 10 In Fig. 5 is shown an embodiment of my invention in which the baffling device is not placed within the casing *b* proper but in a specially constructed chamber *c* offset from casing *b* and communicating therewith by means of a connecting pipe. In this embodiment the vanes and rings while they are mounted in separate casings, will be seen to be subject to the same general principles as the foregoing embodiment since a single shaft 20 serves to mount both.

Having thus described my invention what I claim is:

1. In a radial flow turbine, the combination with a housing, two rotor shafts coaxially mounted within said housing, a disk carried on each rotor shaft, and blades projecting from each of the adjacent faces of said disks in such manner as to cause rotations of said shafts in opposite directions; of pressure receiving surfaces having substantially equal areas with the areas covered by the blades, each of said surfaces being oppositely faced to the blade-bearing surfaces with which it rotates; means for leading the pressure medium from in and about the blades to each of said surfaces opposed thereto; and a plurality of concentric labyrinth rings projecting from each of said pressure-receiving surfaces and housing wall adjacent thereto, said 40 rings overlapping each other in such manner as to form a circuitous passage for the pressure medium whereby pressure is created and

applied to compensate the axial thrust of the blades.

2. In a radial flow turbine of the type described, the combination with a housing and oppositely rotating rotors mounted within the housing; of a substantially cone-formed blade-bearing disk forming a part of each of said rotors, blades mounted on the convexed surface of said disk; concentric labyrinth ring mounted in the concaved surface of the disk; a plurality of perforations in said disk whereby the pressure medium is conveyed from the bladed surface to the ring-bearing surface; and a plurality of labyrinth rings connected with the wall of the housing and adapted to form a running joint with the rings carried by the disk in such manner as to check the passage of the pressure medium, whereby pressure is created upon the pressure-receiving surface of the disk to compensate the axial thrust of the bladed surface.

3. In a radial flow turbine of the type described, the combination with a housing, of a rotor mounted in the housing; said rotor comprising a blade-bearing face, a ring bearing face opposed thereto, passages for conveying the pressure medium from action upon one of said faces to action upon the other of said faces, and a ring-bearing surface carried by the housing and in conjunction with the rotor ring-bearing surface, forming a circuitous passage for the pressure medium whereby an opposite and compensating pressure is caused to react against the axial thrust on said blade-bearing surface.

In testimony, that I claim the foregoing as my invention, I have signed my name in presence of two subscribing witnesses.

BIRGER LJUNGSTRÖM.
